SCARF OR SIMILAR ARTICLE

Dorothy Batzes, Bayonne, N. J.

Application October 28, 1948, Serial No. 149,362

Term of patent 3½ years

(Cl. D3—12)

To all whom it may concern:

Be it known that I, Dorothy Batzes, a citizen of Germany, residing in Bayonne, in the county of Hudson and State of New Jersey, have invented a new, original, and ornamental Design for a Scarf or Similar Article, of which the following is a specification, reference being had to the accompanying drawing, forming a part thereof.

The figure is a plan view of a scarf or similar article, showing my new design. The essential features of my design reside in the portions shown in full lines.

I claim:

The ornamental design for a scarf or similar article, as shown and described.

DOROTHY BATZES.
